UNITED STATES PATENT OFFICE.

NEILSON LLEWELLYN, OF CAINESVILLE, MISSOURI, ASSIGNEE OF ONE-HALF TO JOHN W. SOLEL, OF CAINESVILLE, MISSOURI.

ACETYLENE MINER'S LAMP. Filed May 1, 1916. Serial No. 136,783. Patented Aug. 21, 1917.
1,238,032.

Specification of Letters Patent. Application filed December 13, 1916. Serial No. 136,783.

To all whom it may concern:

Be it known that I, NELSON LLEWELLYN, a citizen of the United States, residing at Cainesville, in the county of Harrison and State of Missouri, have invented new and useful Improvements in Acetylene Miners' Lamps, of which the following is a specification.

This invention relates to improvements in acetylene lamps and more especially with reference to improvements in acetylene lamps such as are used by miners, the object of the invention being to provide a filter for use in the carbide holding and generating bowl of the lamp and between the threaded nipple of the bowl and the threaded cap of the water supply tank and so constructed and arranged as to filter the gas while the same is passing to the burner pipes and to also keep the water supply pipe clear and cause steam to be applied to the threaded connection between the bowl and the water supply tank and thereby prevent dust from settling in said threaded connection and interfering with the assembling and disassembling of the lamp.

The invention consists in the construction, combination and arrangement of devices hereinafter described and claimed.

30. In the accompanying drawings:

Figure 1 is a vertical circular section of the bowl of an acetylene miner's lamp provided with a filter constructed and arranged in accordance with my invention.

35. Fig. 2 is a detailed elevation, partly in section, of the filter.

The miner's lamp here shown is of the usual construction now in common use and comprises the carbide holding and generating bowl 1 and the water supply tank 2. The bowl is provided in its upper side with the threaded nipple 3 and the tank is provided at its lower side with the threaded cap 4 for engagement with said nipple, to effect a threaded connection between the bowl and the tank and enable them to be separated when desired. The usual gas dome 5 is in the upper portion of the cap under the bottom of the tank and the burner pipe 6 leads from said dome and is provided with the usual jet tip 7. A water feed pipe 8 depends from the bottom of the tank. The water feed controlling valve rod 9 extends down through the pipe 8 and is arranged in the 55 guide tube 10 which depends from the top

of the tank. The tank tube has the usual filler opening 11 and hinged closure 12 therefore. The hook 13 for attaching the lamp to the miner's cap is on one side of the tank and cap 4.

In accordance with my invention I provide a filter 14 which is preferably made of sheet metal and which comprises a pan 15 and a spout 16 which extends downwardly from the center of the pan. The pan is of such size that its wall 17 fits in the nipple 3 of the bowl. Said wall has outstanding sheet metal flanges 18 to engage over the upper end of the nipple and between same and the opposing portion of the cap 4 so that the center is firmly clamped between the nipple and cap. The wall is also provided in its outer side with gas filtering grooves 19 which establish gas connection between the bowl and the gas dome 5.

The water feed tube 8 extends through the spout 16. The spout is tapered downwardly and is provided with a correspondingly tapered member 20 which is adjustably fitted thereon so that the length of the spout may be varied according to the depth of the bowl. The spout is provided with an outstruck tongue 21 and the adjustable member 20 has an opening 22 through which the tongue extends. Hence the member 20 may be adjusted as desired and the tongue when bent reversely after being passed through the opening 20 serves to secure the member 20 to the spout at the right adjustment.

The member 20 has a contracted opening 23 at its lower end for the passage of the lower end of the valve rod 10 and is also provided near its lower end with openings 24.

The gas is filtered by passing through the grooves 19 and the openings formed between the flanges 18. The steam which is generated while the water is passing through the lower end of the filter spout by the heat of the moistened carbide is permitted to escape into the carbide through the openings 24 and from which the steam passes up through the filter spout into the pan of the filter and also passes up from the bowl 1 through the filtering grooves 19, together with the gas, and condenses. The flanges 18 serve to spread the water or moisture resulting from the condensation of the steam between the nipple and the cap 4 and thereby

prevent carbid dust from settling between the nipple and the cap and binding them together.

It will be understood that the filter remains in the cap 4 when the dome is unscrewed from the tank, the flanges 18 of the filter pan engaging in the threaded loop of the cap 4.

While I have here shown and described a preferred form of my invention I would have it understood that changes may be made in the form, proportion and construction of the several parts without departing from the spirit of my invention and within the scope of the appended claims.

Having thus described my invention, I claim:

1. In combination with an acetylene gas lamp comprising a carbid holding and generating bowl having a threaded nipple at its upper side and a water supply tank having a threaded cap on its lower side to engage with the nipple, and also provided with a depending water feed tube and a controlling valve rod in said tube; a filter comprising a pan arranged in the nipple of the bowl and having its wall spaced from the wall of the nipple and provided with outstanding flanges to engage between the nipple and cap, the said filter being further provided with filtering grooves in the outer side of its wall and with openings between said

flanges and being further provided with a depending spout in which the water feed tube is arranged, said spout having a contracted opening at the lower end for the passage of the valve rod and being also provided with steam discharge openings near its lower end.

2. In combination with an acetylene gas lamp comprising a carbid holding and generating bowl having a threaded nipple in its upper side and a water supply tank having a threaded cap on its lower side to engage with the nipple of the bowl and also provided with a depending water feed tube and a control valve rod in said tube; a filter comprising a pan arranged in the nipple of the bowl and having its wall spaced from the wall of the nipple and provided with outstanding flanges to engage between the nipple and cap, the said filter being further provided with filtering grooves in the outer side of its wall and with openings between said flanges and being further provided with a longitudinally adjustable depending spout in which the water feed tube is arranged, said spout having a contracted opening at its lower end for the passage of the valve rod and being also provided with steam escape openings near its lower end.

In testimony whereof I affix my signature.

NELSON LLEWELLYN.
